H. G. RICE

BOTTLE CAPPER

Filed May 2, 1925

Inventor:
Harold G. Rice,
by Fisher, Towle, Clapp, Crane, Attnys.

UNITED STATES PATENT OFFICE.

HAROLD G. RICE, OF CHICAGO, ILLINOIS.

BOTTLE CAPPER.

Application filed May 2, 1925. Serial No. 27,378.

My invention relates to bottle cappers and more especially to novel means for raising the operating lever to an elevated position after the lever is depressed as by hand, to apply a cap to a bottle and then released, and for normally retaining the lever in this position so that the same is in an operative raised and convenient position for use in applying the caps.

10 Heretofore, in the type of bottle capping implement such as shown in my Reissue Patent No. 15,222, dated November 8, 1921, when the operating handle was depressed to apply a cap to a bottle, there was no means to automatically raise the handle and the latter would remain in the down position until raised by hand. This rendered it inconvenient to operate the capper since the capped bottle could not be easily removed 15 and another bottle to be capped and the cap to be applied thereto, could not be conveniently placed in position. Besides, this required the use of one hand in raising the handle and holding the same in an elevated 20 position, leaving only one hand free to place the bottle and cap in position, thereby slowing down production.

The present invention embodies a simple construction and novel means for supporting 30 or holding the lever, as well as the rider or slide and capping head carried thereby, in an elevated or operative position for use and so that when the lever or handle is swung downwardly to apply a cap to a bottle and pressure is released therefrom after the cap is applied, the lever will be automatically elevated and maintained in a position to be conveniently grasped and used in applying the caps, being removed or raised away from and 35 above the bottle whereby both hands are free and the bottles and caps may be conveniently placed in position beneath the capping head, the caps applied and the bottles removed without interference or obstruction by the 40 capping head or handle, and the necessity of raising the lever by hand after a cap is applied to the bottle, obviated.

The invention also consists in certain details of construction and the combination 45 and arrangement of parts to be hereinafter specified.

On the drawings:

Fig. 1 is a side elevation of a bottle capper equipped in accordance with the invention;

Fig. 2 is a vertical sectional view taken on 55 the plane of the section line 2—2 of Fig. 1; and

Fig. 3 is a detail side elevation of a cross arm constituting a particular part of the 60 improvement.

Referring to the drawings, a bottle capper of the type shown in my prior patent above referred to, is illustrated. It consists of a frame including a base or base plate 4 adapted to be anchored to a work bench or table 65 and having sides 5 bent upwardly therefrom. The frame proper is of bowed formation and has sides 6 anchored at their lower ends to the sides 5 of the base as indicated at 7 and having their upper portions 70 brought together and connected as by means of rivets 8. The upper portions are straight or flat and rectilinear and provided at their co-acting front edges with rack teeth forming a rack bar 9.

Slidably mounted on the rack bar constituted by the upper portion of the frame, is a rider or slide 10 preferably fashioned from a single plate formed into a rear wall, and sides having extensions 11 suitably spaced 80 apart as by a notch in the lower edge of one extension defining an inner wing prolonged transversely of the rider into engagement with the other extension and the second extension having a notch in its upper edge, 85 while the sides are provided at their forward edges with apertured ears 12 connected by a securing device or rivet 13, the ears being located above the extensions. The space defined by the rear wall, the sides and the 90 inner wing and ears of the rider, accommodates the rack bar so that the rider may move up and down thereon.

A lever 14 is pivoted at 15 so as to fulcrum the same between the extensions 11 and as shown, the handle preferably has its outer or gripping portion shaped from a bent piece of metal to fit the contour of the hand in grasping the same and an inner portion 16 comprising a pair of plates riveted between 100 the sides of the portion 14 as indicated at 17 and their inner edges formed with co-acting teeth providing a segment or segmental rack 18 and meshing with the rack 9. One of the extensions 11 is provided with an extension 105 19 which is prolonged transversely between the extensions 11 at the bottom of the slot therebetween and beneath the shank of the

handle 14 so as to limit the downward swing of the latter when depressed, by contact of the lower edge of the shank of the handle therewith. A capping head 20 is carried by the extensions 11, being preferably riveted to downward extensions thereof extended through slots in the end wall of the head as indicated at 21. This capping head is designed to receive the bottle caps in the application of the latter to the bottles.

While I have described the construction of the bottle capper as set forth in my prior patent and which is preferred in connection with the present improvement, it is to be understood that the details of construction thereof may vary. The particular part of the present improvement consists in mounting a dog which may be in the form of an angular cross arm or bell-crank lever 22 upon the fulcrum 15 outwardly of one extension 11 and retained in position by the headed end thereof. The forwardly extending arm has an angular portion 23 extending outwardly for connection of a contractile coil spring 24 thereto at one end, the opposite or lower end of the spring being anchored to the rider 10 adjacent its bottom edge as by hooking the spring over a lug 25 stamped and pressed out from the bottom edge of one side of the rider or extension thereof as clearly indicated in Figures 1 and 2 of the drawings. The same arm of the cross arm or lever 22 has a lateral inward projection 26 which is designed to engage in back of the rider above the extensions 11 to limit the pivotal movement of the cross arm under the tension of the spring 24 and the free end of the rearwardly extending arm has a lateral inward extension 27 which is designed to engage beneath the shank of the handle or lever 14, whereby the lever is held in a raised position under the action of the spring limited by extension 26 as indicated in Figure 1. Thus, in the use of the device, it will be apparent that the lever will normally be held in a raised position together with the rider and capping head, so as to clear the bottle, whereby the bottles may be conveniently placed in position beneath the capping head, the caps applied and the bottles removed without interference or obstruction by the capping head or handle. This obviates the necessity of raising the lever by hand after a cap is applied to the bottle and leaves both hands of the operator free for other service. When a cap is being applied, the bottle is mounted on the base 4 so that the neck of the bottle will be beneath the capping head, a cap having been previously placed therein. The operator then presses down on the lever 14 and applies the cap to the bottle owing to the downward movement of the rider by rocking of the segment 18 on the rack 9. During the downward movement of the lever the shank thereof engages the extension 27 and rocks

the cross arm 22 on the pivot 15 which is common to the fulcrum of the lever, and raises the forward arm to stretch or extend the spring 24 against its tension, at the same time moving the extension 26 away from the rider. Upon releasing the pressure from the lever 14, the spring 24 will re-act and cause the extension 27 to engage the lever and raise it to an operative position, which movement will swing the rack at the inner end of the lever down and raise the rider, until the extension 26 contacts with the rider. In this position the capping head will have been elevated automatically and removed or raised away from and above the bottle, thus obviating the possibility of the lever dropping down and obstructing the work by interfering with the free insertion of the bottles or caps and requiring manual elevation thereof.

By reason of the cross arm 22 being limited in its movement on the pivot 15 of the lever 14 to a horizontal position, the lever 14 will be supported in a horizontal position for convenient use. It will also be apparent that the lever 14 may be swung upwardly to a substantially vertical position from the substantially horizontal position in which it is supported by the cross arm and spring, to disengage the teeth of the segment 18 from the teeth of the rack bar 9 to permit free sliding movement of the rider 10 over the teeth of the rack bar of the frame, whereby quick initial adjustment of the rider and capping head to bottles of different sizes, may be obtained. It is, of course, to be understood that the upward swing of the lever 14 is independent of the cross arm 22 away from the supporting lug or extension 27 while the cross arm is held against movement under the tension of the spring 24 by engagement of the lug or extension 26 with the rider 10.

While I have shown and described my invention in a preferred form, I am aware that various changes and modifications may be made without departing from the principles of my invention, the scope of which is to be determined by the appended claims.

I claim as my invention:

1. A bottle capper having a frame, a rider mounted for movement on the frame during the operation of the device and having a capping head adapted to receive caps for application to bottles; a lever pivoted to the rider and having operative connection with the frame to move the rider to apply the caps, and a spring-actuated member between the rider and lever and constituting an operative connection therebetween against the tension of which the lever and capping head are moved to capping position and adapted to automatically move and normally raise and support the lever and capping head out of capping position upon pressure being re-

leased therefrom, said member permitting the lever to be raised further out of engagement therewith.

2. In combination with a bottle capper 5 having a base and a frame having a rack, a rider slideable over the rack, a lever pivoted on the rider and having a segment meshing with the rack, a capping head carried by the rider, a cross arm pivoted to the rider 10 and adapted to engage beneath the lever, and spring means between the cross arm and the rider to hold the lever elevated and against the tension of which the lever is moved when lowered.

15 3. In combination with a bottle capper having a base and a frame having a rack, a rider slideable on the rack, a lever pivoted on the rider and having a segment meshing with the rack, a capping head carried by 20 the rider, a cross arm pivoted to the rider and adapted to engage beneath the lever, a spring normally raising the cross arm and lever, and means to limit the movement of the cross arm.

25 4. In combination with a bottle capper having a base and a frame having a rack, a rider slideable on the rack, a lever pivoted on the rider and having a segment meshing with the rack, a capping head carried by 30 the rider, a cross arm pivoted to the rider and adapted to engage beneath the lever, an extension on the cross arm to engage the rider and limit the movement of the cross arm when the lever is raised, means to limit 35 the downward movement of the lever, and a contractile spring between the rider and the cross arm normally tending to raise the lever and adapted to be expanded when the lever is depressed for actuating the rider and 40 capping head.

45 5. In a bottle capper, a frame having a rack, a rider slideable thereon, a lever pivoted to the rider and having a rack segment meshing with the rack to raise and lower the rider, and a spring connection between the rider and lever to raise the lever and rider, and including means connected to the spring and movably connected to the rider and lever, said latter means permitting said lever 50 to be elevated above the position in which normally supported by the spring connection to disengage the segment from the rack and permit quick adjustment of the rider on the rack bar.

55 6. In a bottle capper, a frame, a rider slideable thereon, a lever pivoted to the rider and cooperative with the frame to raise and lower the rider, a cross arm pivoted on the pivot of the lever and adapted to engage the lever, a spring between the cross arm and rider to normally hold the cross arm engaged with the lever and the lever in a substantially horizontal position, said cross arm and spring permitting the lever to be 60 elevated to a substantially vertical position

independently of movement thereof to permit quick free sliding of the rider on the frame upon operative disconnection of the lever with the frame.

7. A bottle capper comprising a frame, a 70 rider slideable on the frame, a lever pivoted on the rider and engaging the frame to reciprocate the rider, a capping head carried by the rider, a member pivoted to the rider and having operative connection with the lever, and means between said member and the rider to actuate the member and hold the lever and capping head out of capping position.

75 8. In combination with a bottle capper 80 having a base and a frame having a rack, a rider slideable on the rack, a lever pivoted on the rider and having a segment meshing with the rack, a capping head carried by the rider, an arm pivoted to the rider and engaged with the lever, and spring means normally raising the arm and lever, and against the tension of which the lever and capping head are moved to capping position.

85 9. In a bottle capper, a frame having a 90 rack, a movable capping member on the frame and movable over the rack, a lever having a toothed segment engaging the rack for moving the capping member into and out of capping position, a movable member 95 adapted to engage the lever, means for actuating the movable member to normally hold the lever slightly above horizontal and the capping member slightly elevated, said means maintaining the segment of the lever 100 in operative connection with the rack but permitting the lever to be moved independently thereof to disengage the segment from the rack and permit quick sliding adjustment of the capping member thereof.

105 10. In combination with a bottle capper having a base and a frame having a rack, a rider slideable over the rack, a lever pivoted on the rider and having a segment meshing with the rack, a capping head carried by the rider, a member pivoted to the rider and adapted to operatively engage the lever, and spring means between the member and the rider to hold the lever elevated while maintaining operative connection between the 110 segment and the rack.

11. In combination with a bottle capper having a base and a frame having a rack, a rider slideable over the rack, a lever pivoted on the rider and having a segment meshing with the rack, a capping head carried by the rider, a member movable relative to the rider and adapted to operatively engage the lever, spring means between the member and the rider to hold the lever partially elevated while maintaining the segment in mesh with the rack, and means to limit the upward movement of the lever under the action of the spring means.

12. In a bottle capper, a base, a frame on 120

the base having a rack, a rider slidable on the rack and having a capping head, a lever pivoted on the rider and having teeth meshing with the rack, spring-actuated means to raise the lever to a substantially horizontal position and also the rider and capping head out of capping position, and means to limit the raising action of the last named means.

- 10 13. In a bottle capper, a base, a frame on the base having notches, a rider slidable on the frame over the notches and having a capping head, a lever pivoted on the rider and having means to engage with the notches 15 for moving the rider upon actuating the lever, and spring means to raise the lever to a point above a horizontal position and also the rider and capping head out of capping position, said means permitting further 20 raising of the lever to disengage the first-named means from the notches.

14. In a bottle capper, a frame, a movable capping member on the frame, a lever having operative engagement with the frame for reciprocating the capping member into and out of capping position upon swinging of the lever, and a retractile spring between the capping member and lever normally holding and supporting said lever in an 30 elevated position and the capping member out of capping position while the lever is in

operative engagement with the frame, said spring being expanded when the lever is swung downwardly to move the capping member into capping position and adapted 35 to permit the lever to be swung upwardly out of operative engagement with the frame to permit free sliding of the capping member on the frame.

15. In a bottle capper, a frame having 40 an upright rack, a rider freely slidable upon the frame, a capping member carried by the rider, a hand lever pivotally mounted upon the rider, the lever being provided with a toothed segment in mesh with the rack to 45 form a fulcrum engagement therewith, and a spring connected to the rider and associated with the lever to automatically swing the lever upwardly upon its fulcrum engagement with the rack from a depressed position when released by the operator and thereby move the rider and capping member upwardly upon the frame and hold the lever and the rider and the capping member elevated, said lever capable of being turned 50 upwardly upon its pivotal mounting from the elevated position in which it is held by the spring to disengage the segment from the rack and thereby permit quick slidale adjustment of the rider along the frame.

HAROLD G. RICE.
